CLAIM

The ornamental design for a phone stand with wireless charger and speaker, as shown and described.

DESCRIPTION

FIG. 1 is a front, right, and top perspective view of a phone stand with wireless charger and speaker showing my new design in a first configuration of use;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is a front, right, and top perspective view thereof, shown in a second configuration of use;

FIG. 11 is a front, right, and top perspective view thereof, shown in a third configuration of use; and,

FIG. 12 is a front, right, and top perspective view thereof, shown in use with a mobile phone.

The dash-dash broken lines in the drawings depict portions of the phone stand with wireless charger and speaker that form no part of the claimed design. The broken lines showing a mobile phone in FIG. 12 depict environmental subject matter and form no part of the claimed design. The dot-dash broken lines in FIGS. 1 and 9 represent the boundaries of the enlarged portion and form no part of the claimed design.
